S. J. TURREFF

RAILWAY TRAFFIC CONTROLLING APPARATUS

Filed Sept. 24, 1924

UNITED STATES PATENT OFFICE.

STANLEY J. TURREFF, OF NEW YORK, N. Y., ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed September 24, 1924. Serial No. 739,556.

To all whom it may concern:

Be it known that I, STANLEY J. TURREFF, a citizen of the United States, residing at New York, in the county of New York and State of New York, have invented certain new and useful Improvements in Railway-Traffic-Controlling Apparatus, of which the following is a specification.

My invention relates to railway traffic controlling apparatus, and particularly to apparatus of the type wherein governing mechanism carried on the train is controlled by energy received from the trackway.

I will describe one form of apparatus embodying my invention, and will then point out the novel features thereof in claims.

The accompanying drawing is a diagrammatic view showing one form of apparatus embodying my invention.

Referring to the drawing, the reference characters 1 and 1^a designate the track rails of a railway along which traffic normally moves in the direction indicated by the arrow. These rails are divided by insulated joints 2 into a plurality of sections A—B, B—C, etc. Located adjacent the exit end of each section is a track transformer designated by the reference character T, with an exponent corresponding to the location.

The secondary of each track transformer is connected across the track rails at the exit end of the section, and the primary of each of these transformers is connected with a transmission line F which is constantly supplied with alternating current by a generator G. Each track section is also provided with a track relay designated by the reference character R, with an exponent corresponding to the location, which relay is

connected across the rails adjacent the entrance end of the section and is responsive to track circuit current supplied to the rails by the track transformer T of the same section. It follows that each track relay R will be energized or de-energized according as the associated track section is unoccupied or occupied.

Means are provided for supplying each track section with a second alternating current which I will term a "loop" current, and for this purpose three resistances 5, 6 and 7 are connected across the rails of each section adjacent the entrance end and inter-

mediate point and the exit end of each section respectively. Loop current is supplied to each section by a transformer designated by the reference character U, with an exponent corresponding to the location. The primary of each loop transformer U is connected with the transmission line F, and the secondary is connected with the resistances 5, 6 and 7, through contacts 3 and 4 of the adjacent track relay R. The control of the loop current for each section by the track relay for the section next in advance is such that when the section next in advance is unoccupied loop current of normal relative polarity is supplied to the rails from the entrance end to the exit end, whereas when the section next in advance is occupied loop current of reverse relative polarity is supplied to the rails from the entrance end to the intermediate point 6, but not from the intermediate point 6 to the exit end of the section. The manner in which this is accomplished is well understood in the art and will be apparent from the drawing without further explanation.

Each track section is provided with a signal designated by the reference character S, with an exponent corresponding to the location. The controlling circuits for these signals are omitted from the drawing because they form no part of my present invention. These signals are controlled in accordance with the usual practice, so that each signal indicates "stop" when the associated section is occupied, "caution" when the associated section is unoccupied and the section next in advance is occupied, and "proceed" when the associated section and the section next in advance are unoccupied.

The reference character V designates a railway train provided with a pair of pick-up coils 8 and 8^a in front of the forward axle, and a second pair of pick-up coils 9 and 9^a at some suitable location, such as at the rear of the locomotive or tender. The pick-up coils 8 and 8^a are included in a receiving circuit a in such manner that the voltages induced in these coils by track circuit current from the track rails are additive, and the pick-up coils 9 and 9^a are included in a second receiving circuit b in such manner that the voltages induced in these coils by loop current in the track

rails are additive. The track receiving circuit *a* controls the supply of current to one winding 12 of a relay H, preferably through the medium of an amplifier 10, whereas the 5 loop receiving circuit *b* controls the supply of current to a second winding 13 of the relay H, preferably through the medium of an amplifier 11. An auxiliary relay J is interposed between the amplifier 10 and the 10 relay winding 12, so that this relay J responds only to track circuit current. The relay H is of the induction motor type, comprising two windings 12 and 13 and a rotor 14 controlling a contact 15.

15 The parts of the train-carried apparatus thus far described are so arranged that when the train occupies a portion of track which is supplied with loop current of normal relative polarity and also with track 20 circuit current, the relay H is energized in normal direction, wherein contact member 15 is swung to the right. When a train occupies a portion of track which is supplied with loop current of reverse relative polarity and also track circuit current, relay H is energized in the reverse direction, wherein contact member 15 is swung to the left. When the supply of either loop current or track circuit current is discontinued, relay 25 H becomes de-energized, so that contact member 15 occupies an intermediate position wherein the back contact 15-18 is closed. Relay J is energized whenever the train occupies a portion of track which is supplied 30 with track circuit current, but is de-energized when the train occupies a portion of track not supplied with such current.

The train V is provided with a brake application magnet L arranged when de-energized to cause an automatic application of the brakes. The train V is also provided with a circuit controller N governed by a speed-responsive device Q which in turn is operatively connected with an axle of the 45 train. When the speed of the train is below 20 miles per hour the arm 32 of circuit controller N is in contact with all three segments 33, 34 and 35; when the speed exceeds 20 miles per hour the arm 32 swings 50 out of contact with segment 35, when the speed exceeds 40 miles per hour the arm 32 swings out of contact with segment 34, and when the speed exceeds 60 miles per hour the arm 32 swings out of contact with segment 33.

The brake application magnet L is controlled jointly by relay H and circuit controller N in the following manner:

When relay H is energized in the normal direction so that contact member 15 is 60 swung to the right, the circuit for magnet L passes from terminal P of a suitable source of current, through contact 15-16 of relay H, wire 31, segment 33 of circuit controller N, arm 32, wire 19, and winding 55

of magnet L to terminal O of the same source of current. This circuit will be closed unless the speed of the train exceeds 60 miles per hour. When relay H is energized in the reverse direction, so that contact member 15 is swung to the left, the circuit for magnet L is from terminal P, through contact 15-17 of relay H, wire 36, segment 34 of circuit controller N, arm 32, wire 19, and winding of magnet L to terminal O. This circuit will be closed, provided the speed of the train does not exceed 40 miles per hour. When relay H is de-energized and relay J is energized, the circuit for magnet L passes from terminal P, through contact 27 of relay J, wires 36 and 37, segment 35 of circuit controller N, arm 32, wire 19, and winding of magnet L to terminal O. This circuit will be closed provided that the speed of the train does not exceed 20 miles per hour. If 80 both relays H and J are de-energized, it will be apparent that so far as the circuits thus far traced are concerned, the brake application magnet L will be de-energized.

The train V is provided with a stick relay K, having a pick-up circuit which passes from terminal P, through back contact 15-18 of relay H, wire 25, front point of contact 20 of relay J, wire 29, and normally open manually operable circuit controller M, wire 22, and winding of relay K to terminal O. It will be seen that this pick up circuit is closed only when relay H is de-energized, relay J is energized, and the engineer is holding circuit controller M closed. Relay K is provided with a stick circuit which passes from terminal P, through back contact 15-18 of relay H, wire 25, back point of contact 20 of relay J, wire 39, contact 23 of relay K, and winding of relay K 95 to terminal O. When relay K is once energized by virtue of its pick up circuit, it will remain energized as long as both relays H and J are de-energized. When relay K is energized an auxiliary circuit for brake application magnet L becomes closed, which circuit passes from terminal P, through contact 24 of relay K, wires 38 and 37, segment 35 of circuit controller N, arm 32, wire 19, and winding of magnet L to terminal O. This circuit will, of course, be closed only when the speed of the train does not exceed 20 miles per hour.

The operation of the apparatus is as follows: As shown in the drawing, section D-E is occupied by a train V, whereas the train V is in section C-D. Track relay R^D being de-energized, loop current of reverse relative polarity is supplied to the rails of section C-D between resistances 5 and 6, but no loop current is supplied to the rails of this section between resistances 6 and 7. Inasmuch as train V is between resistances 5 and 6, this train is receiving 100 loop current of reverse relative polarity and 105 110 115 120 125 130

track circuit current, so that relay H is energized in the reverse direction and relay J is also energized. As the train V passes resistance 6 in section C—D, relay H will 5 become de-energized due to the fact that the train ceases to receive loop current, but relay J will remain energized because the train is still receiving track circuit current from transformer T^E. Brake application 10 magnet L will therefore still be energized through contact 27 of relay J and contact 35—32 of circuit controller N provided the speed does not exceed 20 miles per hour. Assuming that train V' remains in section 15 D—E, then when train V enters section D—E relay H will continue to be de-energized, due to the absence of track circuit current, and relay J will become de-energized for the same reason. This de-energization 20 of relay J will cause brake application magnet L to be de-energized unless the engineer closes circuit controller M prior to entering section D—E. If the engineer does close this circuit controller before relay J 25 becomes de-energized, stick relay K will become energized and will remain energized as long as the trains V and V' both occupy section D—E, so that magnet L will be energized through contacts 24 and 35—32 if 30 the speed does not exceed 20 miles per hour. Assuming that while train V is in section D—E train V' passes out of this section, relay J will become energized because train V is then supplied with track circuit current 35 from transformer T^E, whereupon stick relay K will become de-energized. If train V passes point E while train V' is still in the section immediately to the right of point E, relay J will again become de-energized, 40 so that the brakes will again be applied unless the engineer again operates the circuit controller M.

It will be seen from the foregoing that in order to prevent an automatic application 45 of the brakes the engineer is required to acknowledge every stop signal by closing circuit controller M.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a trackway divided into sections, two sources of train governing current for each section at least one of which 50 is connected across the rails at the exit end of the section, a main train carried relay controlled jointly by currents from said two sources, an auxiliary relay on the train controlled solely by current from said one 55 source, a brake application magnet having

a circuit controlled by a front contact of said auxiliary relay, a stick relay, an auxiliary circuit for said magnet controlled by a front contact of said magnet controlled by a front contact of said stick relay, a pick-up circuit for said stick relay controlled by a back contact of said main relay and a front contact of said auxiliary relay and a normally open manually operable circuit controller, and a holding circuit for said stick 70 relay controlled by a back contact of said auxiliary relay and a back contact of said main relay.

2. In combination, a trackway divided into sections, two sources of train governing current for each section at least one of which 75 is connected across the rails at the exit end of the section, a main train carried relay controlled jointly by currents from said two sources, an auxiliary relay on the train controlled solely by current from said one 80 source, a brake application magnet having a circuit controlled by a front contact of said auxiliary relay, and means including a manually operable circuit controller and a back contact of said main relay for preventing said circuit from being opened due to de-energization of said auxiliary relay.

3. In combination, a trackway divided into sections, two sources of train governing current for each section at least one of which 85 is connected across the rails at the exit end of the section, a main train carried relay controlled jointly by currents from said two sources, an auxiliary relay on the train controlled solely by current from said one 90 source, apparatus normally effective to apply the brakes when both of said relays are de-energized, and means including a manually operable circuit controller for preventing such brake application.

4. In combination, a trackway divided into sections, two sources of train governing current for each section at least one of which 95 is connected across the rails at the exit end of the section, a main train carried relay controlled jointly by currents from said two sources, an auxiliary relay on the train controlled solely by current from said one 100 source, apparatus normally effective to apply the brakes when both of said relays are de-energized, a stick relay effective when energized to prevent such brake application, a normally open manually operable circuit controller, means for energizing said stick 105 relay if said controller is closed while said auxiliary relay is energized, and means for subsequently keeping said stick relay energized while said auxiliary relay is de-energized.

5. In combination, a trackway divided into sections, two sources of train governing current for each section at least one of which 110 source is connected across the rails at the exit end of the section, train carried electro-responsive means controlled jointly by cur- 115

- rents from said two sources, an auxiliary relay on the train controlled solely by current from said one source, apparatus normally effective to apply the brakes when 5 said electro-responsive means and said auxiliary relay are both affected by the absence of said one current, and means including a manually operable circuit controller for preventing a brake application in the absence of said one current.
6. In combination, a trackway divided into sections, a source of current connected across the rails at the exit end of each section, means for supplying to each section a 10 second current which flows through the rails from the entrance end to the exit end or from the entrance end to an intermediate point in the section according as the section next in advance is unoccupied or occupied, a main train carried relay controlled jointly by said two currents, an auxiliary train carried relay controlled solely by the first current, apparatus normally effective to apply the brakes when both of said relays are de-energized, and means including a manually operable circuit controller for preventing 15 such brake application.
7. In combination, a trackway divided into sections, a source of current connected across the rails at the exit end of each section, means for supplying to each section a second current which flows through the rails from the entrance end to the exit end or from the entrance end to an intermediate point in the section according as the section next in advance is unoccupied or occupied, a main train carried relay controlled jointly by said two currents, an auxiliary train carried relay controlled solely by the first current, a brake application magnet having a circuit controlled by a front contact of said auxiliary relay, a stick relay, an auxiliary circuit for said brake application magnet controlled by a front contact of said stick relay, a pick-up circuit for said stick relay controlled by back contact of said 20 main relay and a front contact of said auxiliary relay and a normally open manually operable circuit controller, and a holding circuit for said stick relay controlled by a back contact of said auxiliary relay.
8. In combination, a trackway divided into sections, a source of current connected across the rails at the exit end of each section, means for supplying to each section a 25 second current which flows through the rails from the entrance end to the exit end or from the entrance end to an intermediate point in the section according as the section next in advance is unoccupied or occupied, a main train carried relay controlled jointly by said two currents, an auxiliary train carried relay controlled solely by the first current, apparatus normally effective to apply the brakes when both of said relays are de-energized, a stick relay effective when energized to prevent such brake application, a normally open manually operable circuit controller, means for energizing said stick relay if said controller is closed while said auxiliary relay is energized, and said main relay is de-energized, and means for subsequently keeping said stick relay energized while said auxiliary relay is de-energized.
9. In testimony whereof I affix my signature.
- STANLEY J. TURREFF.
